UNITED STATES PATENT OFFICE.

DUNCAN A. MACCUAIG, OF NEBRASKA CITY, NEBRASKA.

CASTER-RETAINING DEVICE.

No. 921,183.

Specification of Letters Patent.

Patented May 11, 1909.

Application filed August 26, 1908. Serial No. 450,332.

To all whom it may concern:

Be it known that I, DUNCAN A. MACCUAIG, a citizen of the United States, residing at Nebraska City, in the county of Otoe and State 5 of Nebraska, have invented a new and useful Caster-Retaining Device, of which the following is a specification.

The present invention relates to caster retaining devices of the type covered broadly 10 by the claims of a co-pending application, filed simultaneously herewith Serial No. 450,331.

The present invention is in the nature of a division of the above entitled application, 15 and covers one of the embodiments of the invention disclosed in said co-pending application.

The principal object of the present invention is to provide a simple structure, which 20 can be cheaply produced, can be applied to casters of the type now in general use, and will effectively hold a caster in place.

In the accompanying drawings:—Figure 1 is a perspective view of a caster showing the 25 novel retaining device in place thereon. Fig. 2 is a longitudinal sectional view through the same. Fig. 3 is a detail perspective view of retaining device detached from the caster. Fig. 4 is a horizontal sectional view substan- 30 tially on the line 4—4 of Fig. 2.

Similar reference numerals designate corresponding parts in all the figures of the drawings.

In the embodiment disclosed, a caster pint- 35 le 5 is employed, to one end of which is connected the usual yoke 6, and in said yoke is journaled the roller 7. A retaining device is mounted exclusively on the pintle 5, and is formed of a single piece of wire bent into op- 40 positely disposed loops 8 and 9, which embrace the upper or free end of the pintle and are disposed in overlapping relation as shown. The upper loop 8 has its opposite sides bent inwardly as shown at 10, and the end of the 45 pintle above said loop is enlarged as illustrated at 11, thus preventing the longitudinal displacement of the retaining device.

The ends of the loops are provided with retaining arms 12 that are disposed longitudi- 50 nally of the pintle, and are arranged on opposite sides thereof in spaced relation to said pintle. The free or lower ends of the arms 12 are connected by cross portions or rods 13

located on opposite sides of the lower ends of the pintle and movable toward and from said 55 pintle. A keeper strap 14 is located below the lower ends of the arms, and has a central opening 15 through which the pintle passes. This keeper strap is provided with terminal 60 upstanding hooks 16 that limit the outward movements of the cross rods 13, and conse- 65 quently of the arms 12. Said cross rods, however are movable inwardly, inasmuch as the hooks 16 do not limit their inward movements, and thus the arms 12 can yield suffi- 70 ciently to permit the retaining device and caster pintle to be inserted into a socket.

From the foregoing, it is thought that the construction, operation and many advantages of the herein described invention will 75 be apparent to those skilled in the art, without further description, and it will be understood that various changes in the size, shape, proportion and minor details of construction, may be resorted to without departing from 80 the spirit or sacrificing any of the advantages of the invention.

Having thus fully described my invention, what I claim as new, and desire to secure by Letters Patent, is:—

1. The combination with a caster pintle, of a caster retaining device formed of wire and comprising loops that surround the pintle at one end, arms carried by the loops and extending longitudinally of the pintle, and a keeper strap mounted on said pintle and engaging with the free ends of the arms.

2. The combination with a caster pintle, of a retaining device formed of wire and comprising loops that surround the pintle at one 90 end, arms carried by the loops and extending longitudinally of the pintle, cross bars connecting the free ends of the arms and located on opposite sides of the pintle, and a keeper strap mounted on the pintle and having terminal hooks in which the cross bars are mov- 95 ably engaged.

3. The combination with a pintle, having a yoke at one end and a caster roller journaled in the yoke, of a caster-retaining device 100 comprising a single piece of wire formed into oppositely disposed loops which surround the free end of the pintle, arms connected to the ends of the loops and extending longitudinally of the pintle on opposite sides thereof, 105 cross bars integral with and connecting the

free ends of the arms, the said cross bars being located on opposite sides of the pintle, and a keeper strap having a central opening through which the pintle passes, said strap 5 having terminal hooks in which the cross bars are loosely engaged.

In testimony, that I claim the foregoing as

my own, I have hereto affixed my signature in the presence of two witnesses.

DUNCAN A. MACCUAIG.
